CLAIM

The ornamental design for a display device for an electric bicycle, as shown and described.

DESCRIPTION

FIG. 1 is a perspective view thereof;

FIG. 2 is a bottom plan thereof;

FIG. 3 is a top plan view thereof;

FIG. 4 is a right-side view thereof;

FIG. 5 is a left-side view thereof;

FIG. 6 is a front view thereof; and,

FIG. 7 is a back view thereof.

The evenly dashed-lines represent the remainder of the article and do not form part of the claimed design, are directed to environment, and represent unclaimed subject matter.

1 Claim, 7 Drawing Sheets
